UNITED STATES PATENT OFFICE.

BERNT M. BERNTSEN, OF BROOKLYN, NEW YORK.

ROTARY ENGINE.

Application filed February 12, 1921. Serial No. 444,530.

This invention relates to rotary engines, and particularly to engines with rotary pistons and one of the principal objects is to produce a device of this nature which 5 shall be simple of construction, cheap to manufacture, and highly efficient for the purpose for which it is designed.

Another object is to produce a device of this kind in which the rotor body and the 10 piston carrying member rotate about respective fixed axes which are arranged eccentrically.

Another object is to provide the rotor with improved packing means adapted for relative sliding and canting contact with the 15 several pistons.

With these and other objects in view which will be more apparent as the specification proceeds, the invention consists of certain 20 novel construction and combination and arrangement of parts, the essential features of which are hereinafter fully described, are particularly pointed out in the appended claims, and are illustrated in the accompanying 25 drawing, in which:—

Figure 1 is a vertical sectional view of my improved engine.

Figure 2 is a vertical sectional view taken substantially on line 2—2 of Figure 1.

30 Figure 3 is a detailed perspective view of one of the packing members.

Figure 4 is a side elevation of the engine with parts broken away in section.

Like characters of reference refer to like 35 parts in all views.

Referring to the drawing in detail, 10 represents a frame casting which may be constructed in any suitable manner to support the devices hereinafter described. This 40 frame member 10 is provided with a space 11 in which the water or other cooling medium may circulate. A pipe 12 from the carburetor pierces the frame 10 for conducting fuel to the interior thereof and is provided with a valve 13 to admit fuel twice on each revolution of the motor. The control 45 may be of any desired well-known type for opening and closing the valve at the proper times. A way 14 is cut in the inner wall of the frame 10 adjacent to the mouth of pipe 12 so as to permit intake of the fuel during a considerable portion of the stroke of the engine.

50 Mounted in bearings in members 50 and 51 secured in the frame 10 is the drive shaft 15 to which may be connected any system of

power transmission desired. Mounted on shaft 15 to turn therewith is a gear wheel, the teeth of which project through a slot 52 cut in the tubular inner end 53 of member 50 60 and mesh with the teeth of an internal gear 17 formed on or fixedly secured on the inside of a tubular wall 18 of a rotatable piston carrying member mounted eccentrically of shaft 15 and comprising besides the 65 wall 18, an outer flange or wall 19, and four piston blades 20. The wall 19 is provided with four ports 21 intermediate of the pistons 20 for permitting inflow of the fuel to the combustion chambers defined by the 70 pistons, and to permit the exhaust of the burnt gases and products of combustion after explosion. A collar 54 is mounted in the inner end of member 53 and projects into the frame 10. The member 53 also carries suitable bearings for member 18 as at 55.

A second rotary member or rotor is mounted concentric with shaft 15 and comprising a circular plate 22 and inner and outer flanges 23 and 24. The plate 22 is 80 set into one of the inner faces of the frame 10 and the flanges 23 and 24 extend into the opposite inner wall of frame 10 and are supported in suitable ball bearings 25. The walls or flanges 23 and 24 are slotted to embrace the pistons 20 and to permit the necessary 85 relative movement which occurs from the two rotating members moving about different fixed centers.

Straddling each piston 20 is a packing 90 member such as shown in Figure 3, formed with two curved lugs 26 connected by a web 27. The lugs 26 of each packing member are spaced apart sufficiently to permit of the necessary movements of the respective piston 95 therebetween, and the sides of the lugs facing the piston are provided with curved seats in which are placed semi-cylindrical members 28, the flat faces of which bear against the piston so as to prevent escape of 100 fuel etc. from the combustion chamber. The packing members are spaced apart, and springs 29 tend constantly to force them apart.

An exhaust pipe is shown at 30 and 105 pierces the frame member 10, its inner end being situated so as to receive the exhaust from the combustion chambers. An auxiliary exhaust pipe is shown at 31, and through this the greater portion of the remainder of the products of combustion are 110 forced upon the scavenging portion of the

rotation. Pipe 31 is provided with a valve 32 which may be operated by any suitable means to be hereinafter described to open and close twice on each revolution of the 5 rotary members so as to permit very thorough scavenging.

A spark plug 33 of any suitable type may be inserted in the frame 10 for effecting the necessary explosions.

10 In order to facilitate the correct opening and closing of the valves 13 and 32, I provide respective cams 34 and 35 which are fixedly mounted upon a counter-shaft 36. A gear 37 is also fixed to the shaft 36 and 15 meshes with a gear 38 on the shaft 15. The ratio of the gears is such that the cam shaft rotates one revolution to two revolutions of the shaft 15. The cams operate respective valve operating means 39 and 40 of any suitable construction such as shown in Figure 20 4 of the drawings.

In operation, the fuel is drawn from pipe 12 into one of the combustion chambers, and 25 as the chamber enlarges as it passes to its lowest position, none of this charge is expelled through the exhaust pipe 30 when the port 21 comes into register with pipe 30. As the rotation proceeds, the combustion chamber is brought up and owing to the crowding action of the packing members the volume of the combustion chamber is decreased 30 and compression is effected. The pipe 31 is closed by valve 32 at this time so that the charge is not expelled. As the port 35 21 passes plug 33, the charge is ignited and the piston forced clockwise in Figure 1. As the pipe 12 is closed at this time by valve 13, the gases are confined in the combustion chamber until the port 21 is in register with 40 exhaust pipe 30. The succeeding portion of the rotation effects a compression of the remainder of the burnt gases. The valve 32 opens pipe 31 and when port 21 registers with pipe 31 the compressed matter is 45 expelled.

With reference to Figure 1 of the drawings, it will be seen that the chamber #1 is on the intake stroke, chamber #2 is completing the exhaust stroke, chamber #3 is on 50 the compression stroke, while chamber #4 is at the completion of the power stroke. In the operation of the engine, gas is being taken into the chamber #1, and upon clockwise rotation of the rotor, the gas is compressed and when brought into register with the spark plug 33, the same will explode the charge. The chamber #2 during this time has completed the exhaust stroke and taken in charge of gas, and will follow the 55 same operation as the chamber #1 thus causing two successive explosions in the respective chambers #1 and #2 upon the first revolution from the point shown. It will be understood that chamber #3 which 60 is shown on the compression stroke has fired

before either of the chambers #1 and #2 and the same should be disregarded for the present in order to establish a firing order.

After the first revolution of the rotor, the chamber #4 will be the next to fire and 70 while #4 is firing #3 is on the intake stroke, thereby establishing a firing order of chambers 1, 2, 4 and 3 on every two revolutions of the rotor.

While I have shown the engine as constructed for use with gasoline, it is obvious that the engine is capable of operation by steam.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:—

1. In a device of the class described, the 90 combination with the framework thereof, of a rotatable member comprising a plurality of fixedly mounted radiating pistons, a second rotatable member mounted eccentrically of the first said rotatable member and comprising flanges loosely embracing said pistons, and a plurality of packing members yieldingly mounted in the second rotatable member and confined between the flanges thereof and slidably engaging said pistons. 100

2. In a device of the class described, the combination with the framework thereof, of a rotatable member comprising a plurality of fixedly mounted radiating pistons, a second rotatable member mounted eccentrically of the first said rotatable member and comprising flanges loosely embracing said pistons, a plurality of packing members yieldingly mounted in the second rotatable member and confined between the flanges thereof and each embracing a respective one of said pistons, and semi-cylindrical members mounted in said packing members and slidably engaging said pistons. 110

3. In a device of the class described, the combination with the framework thereof, of a rotatable member comprising a plurality of fixedly mounted radiating pistons, a second rotatable member mounted eccentrically of the first said rotatable member and comprising flanges loosely embracing said pistons, a plurality of packing members mounted in the second rotatable member and confined between the flanges thereof and each embracing a respective one of said pistons, springs arranged between adjacent ends of said packing members, and semi-cylindrical members mounted in said packing members and slidably engaging said pistons. 115 120 125

4. In a device of the class described, the 130

combination of the main frame, a shaft rotatably mounted in said frame, a gear fixedly mounted on said shaft, a cylindrical member enclosing said shaft and mounted to rotate eccentrically of said shaft, an internal gear fixedly secured in said cylindrical member and meshing with the first said gear, piston blades radiating from said cylindrical member and defining combustion chambers between them, an outer cylindrical member secured to the outer ends of said piston blades and provided with ports intermediate said piston blades, and a second rotary member mounted concentric with said shaft and provided with means for varying the volume of said combustion chambers for effecting intake, compression and scavenging, said means including a plurality of packing members, and springs between the adjacent ends of said members to force the same in a direction toward its adjacent piston blade.

5. In a device of the class described, the combination of the main frame, a shaft rotatably mounted in said frame, a gear fixedly mounted on said shaft, a cylindrical member enclosing said shaft and mounted to ro-

tate eccentrically of said shaft, an internal gear fixedly secured in said cylindrical member and meshing with the first said gear, piston blades radiating from said cylindrical member and defining combustion chambers between them, an outer cylindrical member secured to the outer ends of said piston blades and provided with ports intermediate said piston blades, a second rotary member mounted concentric with said shaft and provided with means for varying the volume of said combustion chambers for effecting intake, compression and scavenging, said means including a plurality of packing members, and springs between the adjacent ends of said members to force the same in a direction towards its adjacent piston blade, and a feed pipe and a plurality of exhaust pipes extending through said main frame and positioned to register with the ports in the second said cylindrical member, said exhaust pipes being effective one after the other to effect more perfect scavenging.

In testimony whereof I have affixed my signature.

BERNT M. BERNTSEN.
